UNITED STATES PATENT OFFICE.

CLARENCE H. HOWARD, OF ST. LOUIS, MISSOURI, AND JAMES F. DUNN, OF SALT LAKE CITY, UTAH, ASSIGNORS TO DAVIS LOCOMOTIVE WHEEL COMPANY, OF ST. LOUIS, MISSOURI, A CORPORATION OF DELAWARE.

CAR-UNDERFRAME.

No. 845,089.

Specification of Letters Patent.

Patented Feb. 26, 1907.

Application filed December 3, 1906. Serial No. 346,146.

To all whom it may concern:

Be it known that we, CLARENCE H. HOWARD and JAMES F. DUNN, citizens of the United States, residing, respectively, at St. Louis, in the State of Missouri, and at Salt Lake City, in the county of Salt Lake and State of Utah, have jointly invented a new and useful Improvement in Car-Underframes, of which the following is a specification.

Our invention relates particularly to the end sills of a car-underframe, and has for its object to provide a strong, compact, and durable metallic end sill adapted to form a rigid brace to the underframe for resisting shocks from collision, to dispense with a separately-constructed dead-block, and to insure a firm support for the draw-bar of the draft-gear.

The invention consists in features of novelty as hereinafter described and claimed, reference being had to the accompanying drawings, forming part of this specification, whereon—

Figure 1 is a front elevation of our improved metallic end sill; Fig. 2, a top plan view, and Fig. 3 a rear elevation, thereof; Fig. 4, an end view of the same; and Figs. 5 and 6, vertical transverse sections through the sill on lines 5-5 and 6-6, respectively, in Figs. 1 and 2.

Like letters and numerals of reference denote like parts in all the figures.

a represents our improved metallic car end sill, which is preferably composed of cast-steel integral throughout and is in the present case channel-shaped in cross-section, having its web 1 arranged vertically against the ends of the longitudinal car-sills 2 of the underframe (indicated by dotted lines in Fig. 2) and its top and bottom flanges 3 3' projecting outward and horizontally therefrom.

On the bearing-face of the web 1, against the ends of the longitudinal sills 2, are formed, preferably, projecting pockets 4, into which the ends of the sills 2 are preferably tenoned, (or otherwise inserted,) and thereby held immovably in place at the proper distance apart, or the pockets 4 may be formed by depressions in the said face of the web 1 in lieu of projections therefrom, as found desirable.

On the inside of the web 1, preferably midway between the top and bottom flanges 3 3'

of the end sill *a* and adjacent to each pocket 4 of the outer and intermediate longitudinal sills 2, is formed a preferably hollow horizontal cylindrical projection 5, which is united circumferentially to the flanges 3 3' by longitudinal ribs 6, the outer end 5' of the projection 5 being preferably flush with the outer edge of the top flange 3 or equivalent surface of the end sill *a*, and the end 5' and opposite part thereto of the web 1 perforated centrally and transversely to the end sill *a* for the passage therethrough in the assembled portion of the members of the underframe of the screw-threaded end portion of the corresponding truss-rod, (not shown,) which is tightened against the outside of the end 5' by a nut, whereby the end sill *a* and longitudinal sills 2, engaged therewith as described, are rigidly secured together. Furthermore, similar projections 7 are formed on the inside of the web 1 adjacent to each pocket 4 of the middle longitudinal sills 2, and perforated centrally for the passage therethrough of the screw-threaded end portions of the stay-rods, (not shown,) which connect the transverse members of the car-underframe to the end sill.

The end sill *a* is formed on the outside for its entire depth between the top and bottom flanges 3 3', opposite to the web 1 and pockets 4 of the middle longitudinal sills 2, with an extension 8, having its outer face vertical or parallel to the web 1 and otherwise suitably shaped and united to the flanges 3 3' and body of the end sill *a* thereat to form a dead-block, the extension 8 having a bottom horizontal flange 9 at each end thereof, which is flush with the bottom of the extension 8 and projects therewith somewhat below the adjacent bottom surface of the end sill *a*, so as to form a shoulder 10 thereat for engaging a corresponding shoulder on the draft-timber 11, as indicated by dotted lines in Fig. 5, the draft-timbers 11 bearing at their end portions against the under side of the flanges 9.

Through the extension 8 and adjacent part of the end sill *a* are holes 12, and through the flanges 9 are holes 13 for the passage vertically therethrough, respectively, of the bolts 14 15, which secure the draw-bar carrying-irons 16, draft-timbers 11, and end sill *a* rigidly together, all as indicated by dotted lines.

in Figs. 1 and 5. All the said parts—to wit, the pockets 4 for the ends of the longitudinal sills 2, the perforated projections 5 and 7 for the truss and stay-rods, respectively, the extension or dead block 8, and flanges 9—are integral with the body of the end sill *a*, the whole forming a simple, strong, rigid, and inexpensive brace to the underframe, which is thereby enabled to resist shocks from collision without breakage and displacement of its parts.

We do not limit ourselves to a channel-shaped end sill *a*, as the sill may be box, **T**, **I**, or otherwise shaped in cross-section and adapted to be formed integrally with the pockets 4, perforated projections (or their equivalents) 5 and 7, and extension or dead block 8.

What we claim as our invention, and desire to secure by Letters Patent, is—

1. In a car-underframe, a cast-metal end sill integral throughout and having an extension on its front side, and flanges on the extension adapted to form bearings for the draft-timbers, substantially as described.

2. In a car-underframe, the combination of a metallic end sill, channel-shaped in

cross-section, and having its web adjacent to the longitudinal members of the said frame, pockets on the inside of the web adapted to engage the said members, projections on the inside of the web between the flanges of the said sill, each projection and corresponding part of the web having a perforation therethrough transversely to the said sill for the truss and stay-rods of the said frame, and an extension uniting the said flanges on the outside of the said sill opposite to the web and adapted to form a dead-block, all the said parts of the end sill being integral therewith, substantially as described.

In testimony whereof we have signed our names to this specification in the presence of two subscribing witnesses.

CLARENCE H. HOWARD.
